TOY VEHICLE

Frederick B. Schroeder, Cincinnati, Ohio, assignor
of one-half to Thomas Sullivan, Covington, Ky.

Application October 10, 1945, Serial No. 621,420

1 Claim. (Cl. 280—1.17)

1

This invention relates to a toy vehicle. Its purpose is to provide a means for amusing and exercising children in a way most attractive to them. By this I mean forward progress accompanied by and caused by the bouncing of the entire body of the child.

My invention is an improvement upon the cantilever type of hobby horse, which is not capable of forward progress by reason of the rider's up and down motion. This is because this toy has not been provided heretofore with (a) wheels (b) steering gear and (c) means for cancelling impulses of either forward or backward direction. By providing these, I have made a much more attractive toy, i. e., a travelling one out of an original that was purely static.

Referring to the accompanying drawings,

Fig. 1 is a perspective view from the oblique front.

Fig. 2 is a side elevation.

Fig. 3 is a cross section taken on the line 3—3 of Fig. 2.

10 is a centerboard or frame to which are fastened a rear axle 11 and a front axle 12. The latter is pivoted on a bolt 13 for steering purposes. Each axle is provided with right and left wheels 14, preferably of small diameter, i. e., between 6" and one foot. 15 is a strong but flexible cantilever made of spring steel. It is held down at the forward end by bolt 16 and is fulcrumed on the centerboard 10 in the conventional manner. A seat 17 having preferably the usual hobby horse head projecting therefrom and, lower on the cantilever, a conventional footrest 23, preferably adjustable for height. Cords 18 are attached to screw eyes 19 at the top outer ends of axle 12 and pass through other screw eyes 19 at the sides of the horse head. A steering means is thus provided which works after the manner of reins. The dotted-line figure of a child in Fig. 1 shows the position to be assumed by the user.

Under the seat 17 and attached to the centerboard 10, there is pivoted at 21 a short stake 20, which is preferably provided with a rubber tip 22. The stake is slightly longer than the distance from pivot 21 to the ground, so that the stake will trail at an angle approximating the one shown in Figs. 1 and 2. The stake is easily changed with the foot from a rearward inclination to a forward inclination by lifting the vehicle a short distance and then lowering it after the shift has been made.

2

Assuming that the stake 20 is at the angle and direction shown in the drawings, the child has now mounted the seat 17 and is bouncing up and down on the spring cantilever 15. This motion has two components, apparently. One tends to make the vehicle go forward and the other tends to make it go backward. If there were no stake 20 provided, the result would be merely backward and forward oscillation. However, the stake, aided by the rubber tip 22 resists backward motion by pushing against the ground. The forward motion is, however, unresisted so that the vehicle goes forward in short impulses which on a level, smooth surface, are averaged to a continuous progression. If the stake 20 is brought forward in the manner described, so that forward impulses are resisted or cancelled, then the vehicle will go backward. Fig. 2 shows in dotted line the approximate amplitude of 20 bounce that will result in satisfactory progress in either direction.

I claim as my invention:

A toy wheeled vehicle comprising a centerboard, a steerable axle pivoted to the front end 25 thereof, guide means for steering said axle, a cantilever attached to the front of said centerboard, a seat attached to the free end of said cantilever, said guide means being actuatable by the rider from said seat and stake means pivoted upon the side of said centerboard and in angular contact with the surface upon which the vehicle rests, whereby the vehicle is prevented from going in the direction in which the lower end of the stake means is pointed but is free to go in the opposite direction by reason of the force exerted by the rider when he bounces up and down on the free end of the cantilever.

FREDERICK B. SCHROEDER.
